ELEVATOR GUIDE

Walter J. O'Connell, Forest Hills, N. Y.

Application May 10, 1929. Serial No. 361,895

8 Claims. (Cl. 187—95)

My invention relates to improvements in elevator guides.

Its object is to provide a novel form of guide which will hold an elevator car more securely in desired position and which will increase the steadiness of a running elevator car, especially one of the high speed passenger type.

Another object is to provide a structure which will facilitate the operation of lubrication. The 10 most important object of this invention is, however, to increase the safety of the elevator by providing a guide from which the car cannot separate and by providing a structure with which an ordinary car safety device will engage more effectively than has been possible with previous constructions.

These and other objects will appear from the following specification in which I will describe the invention, the specific features of which I 20 will point out in appended claims.

Referring to the drawing,

Fig. 1 is a perspective view of a portion of an elevator guide rail which is made according to and embodies the present invention;

Fig. 2 is a sectional plan view of a modified form of guide rail which also embodies this invention;

Fig. 3 is a view similar to that shown in Fig. 2 showing a still further modified form of guide 30 rail which also embodies this invention;

Fig. 4 shows somewhat diagrammatically, the frame of an elevator car with safety device actuating mechanisms of known constructions;

Fig. 5 is a sectional plan view of a portion of 35 a guide rail and its contacting shoe, together with a portion of a car safety device of known construction. The section in this figure is taken on the line 5—5 of Fig. 4 but drawn on a somewhat larger scale;

Fig. 6 is an elevation, partly in section, of the parts which are shown in Fig. 5, the section being taken on the line 6—6 of Fig. 5;

Fig. 7 is a sectional plan view of the guide rail and its contacting shoe taken on the line 7—7 of 45 Fig. 4; and

Fig. 8 is a plan view of a safety device especially adapted to cooperate with my improved guide rail.

In the drawing, the guide rail shown comprises in every case a base or flange 10 by means of which it is secured to the building or structure in which the elevator car runs. The guide rail projects from this base or flange, preferably from the center thereof, in the usual manner, 55 but with oppositely flaring finished surfaces

11—11. In every form of the invention there is a third bearing surface which, in the preferred form, as shown in Fig. 1, is a concave surface 12.

A somewhat similar depressed bearing face may be formed as shown in Fig. 2, with two converging flat surfaces 12A or, if desired, the third bearing face may be a flat surface as shown at 12B in Fig. 3.

The frame of the elevator car shown in Fig. 4 is designated by 20. It comprises the usual parts, which need not be enumerated, except to point out that the cross head 21 is suspended from cables 22 which are secured to a plate 23, or the ends of said cables are enlarged as shown so that they cannot be pulled upwardly through the plate 23. Springs 24—24 are interposed between the plate 23 and the cross head 21. 25 is a bell crank lever pivotally mounted upon the cross head and connected by suitable linkages with the plate 23 and the rods 26 which extend down to and are connected with the car safety device.

It may be seen that the parts thus briefly described are so arranged that if the cables 22 break or become slack for any reason, the rods 26 will be raised by the action of the springs 24 through the parts which have been pointed out.

27 is a rope or cable which extends to a speed governor device and which is arranged to run with the car at normal speeds but which will be arrested automatically if the car attains an abnormal speed. When this governor rope is thus arrested, it will cause the rods 26 to be raised through the linkage shown at 28. As this too is a well known construction and operation, it is only referred to somewhat briefly.

The elevator car is provided with suitable shoes which run over the three faces of my improved guide rail. One of such shoes is shown at 30 in Figs. 5 and 6. In this case a part of the shoe is cut away to form an inclined recess 31, in which is placed a friction roller 32. The lower end of the rods 26 extend under these friction rollers 32, as at 29, it being understood that there is one such arrangement at each side of the car. This arrangement forms what I have called an elevator safety device and is one of many well known types of safeties, but as the safety device per se forms no part of the present invention, it will not be described further, except in connection with the description of the operation of the invention. The elevator shoe 30 above the safety device is shown somewhat in detail in Fig. 7. 33 is a pad which engages the concave surface 12 of the guide rail. This may be an integral part of the shoe but it is sometimes preferable to make it a separate ele-

ment so that it may be replaced when worn. 34—34 are side pads which are pressed inwardly by means of springs 35 against the flat faces 11 of the guide rail. One or more of these spring pressed pads may be used, as desired.

The operation is as follows: In the first place, when the surface 12 or 12A is concaved, as shown in Figs. 1 and 2, that part of the car shoes 30 which runs on this face of the guide rail will suffice to hold the car in proper alinement. Furthermore, because of this peculiar shape of this running face of the guide rails, its lubrication is facilitated. This feature is especially useful in connection with high speed cars, as they are sufficiently guided with a minimum of bearing surfaces and with efficient lubrication.

But the same shoes 30 are provided as has been shown with surfaces which bear upon the surfaces 11, which, because of their flaring relation, effectively prevent removal of the shoe from the guide rail. This feature, of course, adds greatly to the safety of the operation of the car and is operative even when the outer running face is a plane surface, as shown at 12B in Fig. 3. Furthermore, any tendency of the car to pull the shoe away from the guide has the effect of centering the car on the guide. Consequently, if the guide rail is provided with a concave face, any pressure of the car toward or away from the guide rail tends to center the car.

A great advantage of the use of this novel form of elevator guide rail is that when an element of a car safety device is applied to any one of the three running faces of the guide rail, the car will be securely locked to all three running faces of the guide rail. For example, if a type of car safety device such as that which is shown in Figs. 5 and 6 is employed, and the friction roller 32 is raised by the rod 26, it will, upon running between the inclined face of the recess 31, become wedged between this face of the recess, which is a part of the shoe 30, and one of the running faces 11 of the guide rail. This will cause the opposite face of the shoe to be pulled into engagement with the other running face 11 of the guide rail and because of the inclined relation of these two running faces 11, the part of the shoe 30 which engages the face 12 of the guide rail will also be forced into tight contact therewith. Thus the shoe will become locked to the guide rail by engagement with all three of the running surfaces of the latter.

The safety device shown in Fig. 8 is especially designed to cooperate with the improved guide rail disclosed herein. 45 is a shaft arranged to be rotated in the usual manner when conditions require the application of the safety device, to move member 44 away from the guide rail. This member 44 has inclined sides which are thus drawn between the ends 43 of pivoted levers, forcing them apart. On the other ends of these levers are pads 42 which, by the aforesaid operation, are forced into locking engagement with the inclined faces 11 of the guide rail. As this may have a tendency to pull the guide rail away from its supporting structure, the arrangement shown may be provided.

41 is a third pad, preferably of bronze, adapted to coact with the widened face 12 of the guide rail. This pad is on a cross-bar 40 which is drawn by springs 46 toward arms 47 projecting laterally from the pivoted arms 43. Set-screws 48 are provided, by means of which the space between the pad 41 and the face of the guide rail may be adjusted, and which serve to move the pad into contact with the widened face of the

guide shoe whenever the safety device is actuated.

It will be seen that by flaring the surfaces 11, the surface which is adjacent the car will have maximum width per weight of rail, and that concaving this widened face centralizes the car, eliminates wear on the side surfaces, and provides a groove for lubricant. This invention is intended primarily for use with elevator installations, for the car guides or for the counterweight guides, or for both, but is doubtless useful for other purposes.

What I claim is:

1. A guide rail having a wide transverse concaved front face and two side faces inwardly converging therefrom said front face being arranged to center a member slidably mounted on the rail.

2. A guide rail having a wide transverse inwardly curved front face and two side faces inwardly converging therefrom said front face being arranged to center a member slidably mounted on the rail.

3. In an elevator installation the combination with a car of a guide rail having a wide transverse concaved face adjacent the car and two flat faces inwardly converging therefrom, and a shoe on the car having surfaces adapted to slide over the three faces of said guide rail, the surface of said shoe which slides over the concaved surface of the guide rail being of convex form to fit said concaved face to center the car on the rail.

4. In an elevator installation, the combination with a car of a guide rail having a wide transverse inwardly curved front face adjacent the car and two flat faces inwardly converging therefrom, and a shoe on the car having surfaces adapted to slide over the three faces of said guide rail, the surface of said shoe which slides over the inwardly curved surface of the guide rail being outwardly curved to cooperate therewith.

5. In an elevator installation, the combination with a car of a guide rail having a wide transverse inwardly curved front face adjacent the car and two flat faces inwardly converging therefrom and a shoe on the car having surfaces adapted to slide over the three faces of said guide rail, the surface of said shoe which slides over the inwardly curved surface of the guide rail being outwardly curved to cooperate therewith, and a car safety device adapted to effect an engagement of the surfaces of the guide rail.

6. In an elevator installation, the combination with a car of a guide rail having a wide transverse concave front face adjacent the car and two side faces inwardly converging therefrom, a shoe on the car having a convex pad adapted to slide over said front face of the guide rail to center the car on the rail and separate side pads adapted to slide over the side faces of the guide rail, and springs pressing said side pads against the rail.

7. In an elevator installation, the combination with a car of a guide rail having a wide transverse concave front face adjacent the car and two flat side faces inwardly converging therefrom, a shoe on the car having a removable pad affixed thereto having a convex surface adapted to slide over said front face of the guide rail to center the car on the rail and separate side pads adapted to slide over the side faces of the guide rail, and springs pressing said side pads against the rail.

8. In an elevator installation, the combination with a car of a guide rail having a wide transverse concaved front face adjacent the car and

two flat faces inwardly converging therefrom, a safety device on the car comprising three members arranged to engage said three faces of the guide rail that one of said three members which engages said front face being of convex form to fit said concaved face to center the car on the rail, and means for forcing two of the members against the side faces of the rail and causing the pressure thereof to force the third member against the front face of the rail.
